(57) **CLAIM**

The ornamental design for a frame toy brick with appendages as shown and described.

DESCRIPTION

FIG. 1 is a top perspective view of a frame toy brick with appendages.

FIG. 2 is a bottom perspective view of the frame toy brick with appendages.

FIG. 3 is a second, top perspective view of the frame toy brick with appendages.

FIG. 4 is a second, bottom perspective view of the frame toy brick with appendages.

FIG. 5 is a side perspective view of the frame toy brick with appendages.

FIG. 6 is a second, side perspective view of the frame toy brick with appendages.

FIG. 7 is a third, side perspective view of the frame toy brick with appendages.

FIG. 8 is a fourth, side perspective view of the frame toy brick with appendages.

FIG. 9 is a top plan view of the frame toy brick with appendages.

FIG. 10 is a bottom plan view of the frame toy brick with appendages.

FIG. 11 is a front plan view of the frame toy brick with appendages.

FIG. 12 is a back plan view of the frame toy brick with appendages.

FIG. 13 is a side plan view of the frame toy brick with appendages.

FIG. 14 is a second, side plan view of the frame toy brick with appendages.

FIG. 15 is a top perspective view of a second embodiment of the frame toy brick with appendages.

FIG. 16 is a bottom perspective view of the second embodiment of the frame toy brick with appendages.

FIG. 17 is a second, top perspective view of the second embodiment of the frame toy brick with appendages.

FIG. 18 is a second, bottom perspective view of the second embodiment of the frame toy brick with appendages.

FIG. 19 is a side perspective view of the second embodiment of the frame toy brick with appendages.

FIG. 20 is a second, side perspective view of the second embodiment of the frame toy brick with appendages.

FIG. 21 is a third, side perspective view of the second embodiment of the frame toy brick with appendages.

(Continued)

FIG. 22 is a fourth, side perspective view of the second embodiment of the frame toy brick with appendages. (56)

FIG. 23 is a top plan view of the second embodiment of the frame toy brick with appendages.

FIG. 24 is a bottom plan view of the second embodiment of the frame toy brick with appendages.

FIG. 25 is a front plan view of the second embodiment of the frame toy brick with appendages.

FIG. 26 is a back plan view of the second embodiment of the frame toy brick with appendages.

FIG. 27 is a side plan view of the second embodiment of the frame toy brick with appendages; and,

FIG. 28 is a second, side plan view of the second embodiment of the frame toy brick with appendages.

The broken lines in the figures show features of the frame toy brick with appendages that form no part of the claimed design.
